UNITED STATES PATENT OFFICE.

EDNA A. HUTCHISON, OF INDEPENDENCE, MISSOURI.

DESIGN FOR A DOLL.

59,491.

Specification for Design.

Patented Oct. 25, 1921.

Application filed July 5, 1921. Serial No. 482,609. Term of patent 3½ years.

To all whom it may concern:

Be it known that I, EDNA A. HUTCHISON, a citizen of the United States, residing at Independence, in the county of Jackson and State of Missouri, have invented a new, original, and ornamental Design for Dolls, of which the following is a specification, reference being had to the accompanying drawing, forming part thereof.

The figure is a front elevation of a doll, showing my new design.

I claim:

The ornamental design for a doll, as shown.

EDNA A. HUTCHISON.

Witnesses to signature:

VIRLEEN M. GUDGELL,
JOHN W. HINDS.
